His Attorney.

UNITED STATES PATENT OFFICE

2,614,398

TUBE SEAL

Robert E. Goure, Erie, Pa., assignor to General Electric Company, a corporation of New York

Application December 27, 1951, Serial No. 263,676

3 Claims. (Cl. 62—99)

1

My invention relates to refrigerating apparatus and pertains more particularly to refrigerated cabinets.

Refrigerated cabinets usually comprise an outer case and a liner. In home freezers, for example, evaporator tubing is secured to the exterior surfaces of walls of the liner in heat exchange relationship therewith. The space between the outer case and the liner is usually packed with insulating material and sealed. The sealing prevents entrance of moisture into the space between the case and liner and thereby minimizes cabinet corrosion and damage to the insulating material. However, in such a construction it is essential that tubes pass through the outer case for supplying refrigerant to and exhausting refrigerant from the evaporator tubing.

Accordingly, it is the primary object of my invention to provide in a refrigerated cabinet construction including a sealed space wherein evaporator tubing is housed, improved means whereby tubes to and from said evaporator tubing may pass into the sealed space without affecting the sealing thereof.

Further objects and advantages of my invention will become apparent as the following description proceeds and the features of novelty which characterize my invention will be pointed out with particularity in the claims annexed to and forming a part of this specification.

In carrying out the objects of my invention, I provide a refrigerated cabinet construction comprising a liner and an outer case having a face portion. Evaporator tubing is secured to the exterior surfaces of the walls of the liner. A capillary tube to the evaporator tubing and a suction line therefrom are secured together in heat exchange relationship and pass into the otherwise sealed space between the outer case and liner through a passage in the side wall of the outer case at a point adjacent the face portion thereof. The tubes pass through a passage formed in a block of displaceable material, such as rubber. A bracket is provided for cooperating with the block. Fastening means are provided for drawing the bracket outwardly against the inner side of the outer case and upwardly against the under side of the face portion whereby the block is displaced. Displacement of the block effects sealing about the passage in the outer case and constricts the block passage for effectively sealing about the tubes.

For a better understanding of my invention, reference may be had to the accompanying drawings in which Fig. 1 is a rear-elevational view of a home freezer cabinet; Fig. 2 is a section taken along the line 2—2 in Fig. 1; Fig. 3 is a section taken along the line 3—3 in Fig. 2; Fig. 4 is a cross-sectional view through the sleeve and tub-

2

ing therein; and Fig. 5 is a perspective view of the displaceable rubber block.

In Fig. 1, I have shown, by way of example, a home freezer cabinet 1 including an outer case 2 and a suitably hinged lid 3. As seen in Fig. 2, the freezer cabinet 1 further includes a liner 4, all the walls of which are suitably spaced from those of the outer case 2. Secured to the exterior surface of the walls of the liner 4 in heat exchange relationship therewith are parallel passes of tubing of an evaporator 5.

The space between the walls of the outer case 2 and the liner 4 is packed with suitable heat insulating material 6. The outer case 2, as seen in Figs. 2 and 3, is formed about its upper edges with a face portion 7. A breaker strip 8 extends between the upper edges of the liner 4 and the inner edges of the outer case face portion 7. With this construction the insulated space between the outer case 2 and the liner 4 is sealed, minimizing entrance of moisture through the outer case into the space between the outer case and liner, which would result in cabinet corrosion and damage to the insulation by the collection of ice therein.

Included in the present construction is means for providing a sealed passage for a capillary tube 9 and a suction line 10 into the sealed space between the outer case and the liner. The capillary tube 9 is connected to the inlet side of the evaporator 5 and liquid refrigerant is supplied therethrough. The suction line 10 is connected to the outlet side of the evaporator 5 and vaporous refrigerant is exhausted therethrough. The capillary tube 9 and the suction line 10 are secured together in heat exchange relationship and are together bent to form a tubing elbow generally designated 11 in Fig. 2.

As best seen in Figs. 1, 2 and 3, the rear wall 40 of the cabinet 1 is formed to include a vertical channel 12. The upper end of the channel 12 terminates in a passage 13 adjacent the face portion 7 and leading into the otherwise sealed space between the outer case 2 and the liner 3. One 45 side of the elbow 11 extends from the passage 13 and is disposed in the channel 12 for running to the machinery compartment (not shown) of the cabinet. This side of the elbow is covered by a sleeve 14 of rubber or the like for minimizing 50 condensation thereon.

Fitted on the elbow 11 is a short sleeve 15 of metal or the like. As shown in Fig. 4, the space between the inner periphery of the sleeve 15 and the outer peripheries of the capillary tube 9 and the suction line 10 is sealed by being filled with 55 solder or the like designated 16.

The sleeve 15 and the portion of the elbow 11 upon which it is fitted pass through a passage 17 formed in a member or block 18 of displaceable material such as rubber. As best seen in Figs.

2 and 5, the passage 17 in the block 18 is inclined. The inclination of the passage 17 is such as to be substantially parallel to the outer periphery of the sleeve 15. Thus, there is maximum surface engagement between the sleeve and the block passage. The lower end of the passage 17 is substantially in register with the passage 13 in the outer case 2. The upper end of the passage 17 is in substantial register with a passage 19 in a bracket 20 of L-shaped cross section provided for cooperating with the block 18. Machine screws 21 pass through the rear wall of the outer case 2, the block 18 on either side of the passage 17, the upright leg of the bracket 20 and thread into nuts 22 which are preferably secured to the bracket. By tightening the screws 21, the bracket 20 is drawn outwardly toward the inner side of the side wall of the outer case 2. Other machine screws 23 pass through the face portion 7 of the outer case on either side of the block 18, pass through the horizontal leg of the bracket 20 and thread into nuts 24 which are also preferably secured to the bracket. By tightening the screws 23, the bracket is drawn upwardly toward the underside of the face portion 7. When the bracket 20 is drawn sufficiently upwardly and outwardly in the manners just described, the block 18 is squeezed and displaced. Displacement of the block 18 is effective both for sealing about the passage 13 in the outer case 2 and for constricting the passage 17 in the block. Constriction of the passage 17 effects sealing about the sleeve 15. Thus, the tubing to and from the evaporator 5 is afforded passage into the sealed space between the outer case 2 and the liner 4 without affecting the sealing thereof.

While I have shown and described a specific embodiment of my invention, I do not desire my invention to be limited to the particular form shown and described and I intend by the appended claims to cover all modifications within the spirit and scope of my invention.

What I claim as new and desire to secure by Letters Patent of the United States is:

1. In a refrigerated cabinet construction including an outer case having a wall and a face portion, a liner and means whereby a sealed space is provided between said outer case and said liner, means for providing a sealed passage of tubing into said sealed space comprising; a passage in said wall adjacent said face portion for affording passage of said tubing therethrough, a member of displaceable material, said member having a passage for receiving said tubing, said member being engageable with said outer case wall about said passage therein and with said face portion, a bracket cooperating with said member, and means for drawing said bracket toward both said outer case wall and said face portion whereby said member is displaced, displacement of said member being effective for sealing about said passage in said outer case wall and for constricting said passage in said member for sealing about said tubing.

2. In a refrigerated cabinet construction including an outer case having a wall and a face portion, a liner, evaporator tubing secured to the exterior surfaces of the walls of said liner and means whereby a sealed space is provided between said outer case and liner, means for providing a sealed passage of a capillary tube and a suction line into said sealed space for connection to said evaporator tubing comprising; a passage in said wall of said outer case and adjacent said face portion for affording pas-

sage of said capillary tube and said suction line therethrough, a sleeve fitted about both said capillary tube and said suction line just inside of said outer case wall, means for sealing the space between said sleeve and said capillary tube and suction line, a block of displaceable material, said block having a passage for receiving the portions of said capillary tube and said suction line having said sleeve thereon, said block being engageable with the inner side of said outer case wall about said passage therein and the inner side of said face portion, a bracket cooperating with said block, and means for drawing said bracket toward both said outer case wall and said face portion whereby said block is displaced, displacement of said block being effective for sealing about said passage in said outer case wall and for constricting said passage in said member for sealing about said sleeve.

3. In a refrigerated cabinet construction including an outer case having a wall and a face portion, a liner, evaporator tubing secured to the exterior surfaces of the walls of said liner and means whereby a sealed space is provided between said outer case and liner, means for providing a sealed passage of a tubing elbow consisting of a capillary tube and a suction line secured together in heat exchange relationship into said sealed space for connection to said evaporator tubing comprising; a channel formed in a side wall of said outer case, said channel terminating at its upper end in a passage adjacent said outer case face portion for admitting said elbow into said sealed space, a sleeve fitted on said elbow just inside of said outer case, means whereby the space between the inner periphery of said sleeve and the outer peripheries of said capillary tube and said suction line is sealed, a block of rubber conforming to the inner side of said outer case wall about said passage therein and the inner side of said face portion, a passage in said rubber block for receiving said sleeve on said tubing elbow, said block passage running substantially parallel to the outer periphery of said sleeve for maximum surface engagement therebetween, one end of said passage in said block being substantially in register with said passage terminating said channel, an L-shaped bracket cooperating with at least two sides of said rubber block, a passage in one leg of said bracket being substantially in register with the other end of said block passage for affording passage of said tubing elbow therethrough, means engaging said outer case wall and one leg of said bracket for drawing said bracket toward said outer case wall, and means engaging said face portion of said outer case and the other leg of said bracket for drawing said bracket toward said face portion, whereby said block is displaced, displacement of said block being effective for sealing about said passage in said outer case wall and for constricting said passage in said block for sealing about said sleeve.
